UNITED STATES PATENT OFFICE.

DAVID J. CARTWRIGHT, OF BOSTON, ASSIGNOR TO JOHN S. POTTER, OF NEWTON, MASSACHUSETTS.

CEILING-ROSETTE FOR INCANDESCENT LAMPS.

SPECIFICATION forming part of Letters Patent No. 450,991, dated April 21, 1891.

Application filed November 10, 1890. Serial No. 370,944. (No model.)

To all whom it may concern:

Be it known that I, DAVID J. CARTWRIGHT, a citizen of the United States, and a resident of Boston, in the county of Suffolk and State of Massachusetts, have invented new and useful Improvements in Ceiling-Rosettes for Incandescent Lamps, of which the following, taken in connection with the accompanying drawings, is a specification.

- 10 This invention relates to improvements in ceiling-rosettes for connecting the lamp-wires of incandescent electric lamps to the circuit-wires in a detachable manner, so that said circuit-wires may readily be attached to the 15 lamp-wires in case of a renewal of the latter, as will hereinafter be more fully shown and described, reference being had to the accompanying drawings, in which—

Figure 1 represents a top plan view of the 20 improved ceiling-rosette. Fig. 2 represents a bottom plan view of the same; and Fig. 3 represents a central longitudinal section on the line X X shown in Fig. 1.

Similar letters refer to similar parts wherever they occur on the different parts of the drawings.

A in Fig. 3 represents the ceiling to which the improved rosette is to be attached, and B represent the parallel circuit-wires leading 30 from the dynamo, as usual.

To the ceiling I secure my improved rosette, which consists of a block C, preferably made of porcelain or equivalent non-conducting material, said block being made in a single piece, 35 and having on its upper side an annular lip or ring C', as shown in the drawings, the upper side of which is held against the under side of the ceiling A, preferably by means of fastening-screws going through perforations D D in 40 the block C, as shown in Figs. 1 and 2. The annular lip or ring C' has a pair of diametrically-arranged cut-away portions c c, adapted to receive the radial metal arms E E, which are secured in a detachable manner to the 45 block C, preferably by means of screws e e, passing loosely through perforations in the block C, and having their upper ends screw-threaded and screwed through threaded perforations in said radial metal arms E E, as 50 shown in the drawings. The inner ends of the said radial metal arms E E are provided with binder-screws E' E', by means of which the upper ends of the lamp-wires F F are metallically connected to said radial arms E E.

C'' is a central vertical perforation in the block C, through which are passed the silk-spun or coated lamp-wires F F, as shown in the drawings. The radial arms E E have their outer portions projecting outside of the block C, and are provided with binder-screws 60 E'' E'', by means of which said radial arms are metallically connected to the respective circuit-wires B B, as shown in the drawings. If so desired, a fuse may be interposed between each of the binder-screws E' and its 65 corresponding lamp-wire, for the purpose of preventing the latter from being blown in case an excessive or abnormal current should be conducted to the metallic arms of the rosette, without departing from the essence of 70 my invention. As such fuse or fusible wire is well known in the art to which this invention relates, it is not represented in the drawings.

By the use of my device the lamp-wires may 75 easily be renewed at any time simply by detaching the block C from the ceiling and circuit-wires, after which the lamp-wire may be renewed by detaching the old wires from the binder-screws E' E', and replacing them with 80 new ones to be attached to said binder-screws, after which the rosette is secured to the ceiling and its arms E E connected to the circuit-wires B B, as before.

Having thus fully described the nature, 85 construction, and operation of my invention, I wish to secure by Letters Patent and claim—

The herein-described ceiling-rosette for incandescent lamps, consisting of a block of insulating material having an annular ring or 90 lip on its upper side, combined with a pair of radial metal arms secured to said block and projecting through cut-away portions in the annular lip, said arms having their inner and outer ends provided with binder-screws for 95 securing them to the respective lamp and circuit wires, substantially as and for the purpose set forth.

In testimony whereof I have signed my name to this specification, in the presence of 100 two subscribing witnesses, on this 1st day of November, A. D. 1890.

DAVID J. CARTWRIGHT.
